(57) **CLAIM**

I claim the ornamental design for a vaping device, as shown and described.

DESCRIPTION

FIG. 1 is a top perspective view of a first embodiment of a vaping device showing the claimed design, a swivel cover thereof being in a first configuration;

FIG. 2 is a bottom perspective view of the first embodiment of the vaping device;

FIG. 3 is a front elevation view of the first embodiment of the vaping device;

FIG. 4 is a rear elevation view of the first embodiment of the vaping device;

FIG. 5 is a right-side elevation view of the first embodiment of the vaping device;

FIG. 6 is a left-side elevation view of the first embodiment of the vaping device;

FIG. 7 is a top plan view of the first embodiment of the vaping device;

FIG. 8 is a bottom plan view of the first embodiment of the vaping device;

FIG. 9 is a top perspective view of the first embodiment of the vaping device, partially exploded, the swivel cover being in a second configuration and a mouthpiece cover thereof being removed;

FIG. 10 is a top perspective view of a second embodiment of the vaping device, the swivel cover thereof being in the first configuration;

FIG. 11 is a bottom perspective view of the second embodiment of the vaping device;

FIG. 12 is a front elevation view of the second embodiment of the vaping device;

FIG. 13 is a rear elevation view of the second embodiment of the vaping device;

FIG. 14 is a right-side elevation view of the second embodiment of the vaping device;

FIG. 15 is a left-side elevation view of the second embodiment of the vaping device;

FIG. 16 is a top plan view of the second embodiment of the vaping device;

FIG. 17 is a bottom plan view of the second embodiment of the vaping device; and,

FIG. 18 is a top perspective view of the second embodiment of the vaping device, partially exploded, the swivel cover being in the second configuration and the mouthpiece cover thereof being removed.

The drawings show two embodiments that do not differ substantially from each other, in which FIGS. 1 to 9 show the first embodiment and FIGS. 10 to 18 show the second embodiment.
